US0D1072107S

(12) **United States Design Patent** (10) **Patent No.:** **US D1,072,107 S**
(45) **Date of Patent:** **** Apr. 22, 2025**

(54) **SHAPE-TRANSFORMING TOY**

(71) Applicant: **Guangdong Yangbang Science and Technology Industry Co., Ltd.**, Shantou (CN)

(72) Inventor: **Jianwei Chen**, Shantou (CN)

(73) Assignee: **Guangdong Yangbang Science and Technology Industry Co., Ltd.**, Shantou (CN)

(**) Term: **15 Years**

(21) Appl. No.: **29/887,425**

(22) Filed: **Mar. 21, 2023**

(30) **Foreign Application Priority Data**

Nov. 21, 2022 (CN) 202230775007.6

(51) **LOC (15) Cl.** **21-01**

(52) **U.S. Cl.**

USPC **D21/579**; D21/621

(58) **Field of Classification Search**

USPC D21/479, 576, 578-584, 594-604, 606,

D21/608-611, 614-622, 626, 650-657;

D15/99

CPC A63H 3/04; A63H 33/03; A63H 3/16

See application file for complete search history.

(57) **CLAIM**

The ornamental design for a shape-transforming toy, as shown and described.

DESCRIPTION

FIG. 1 is a front, right and top perspective view of a shape-transforming toy, showing my new design; FIG. 2 is a rear, left and bottom perspective view thereof; FIG. 3 is a front view thereof;

FIG. 4 is a rear view thereof;

FIG. 5 is a left side view thereof;

FIG. 6 is a right side view thereof;

FIG. 7 is a top plan view thereof; and,

FIG. 8 is a bottom plan view thereof.

The broken lines shown in the drawings illustrate portions of the shape-transforming toy that form no part of the claimed design.

1 Claim, 8 Drawing Sheets
